191

FIG. 1 is a front elevational view of a light emitting gas discharge matrix display panel showing our new design, the rear being identical to the front shown except that the plate nearest the viewer becomes the most remote from said viewer and vice versa, with the gas fill tubulation projecting toward the viewer;

FIG. 2 is a bottom plan view thereof, the top being a mirror image of the bottom shown; and

FIG. 3 is an elevational view taken from one side thereof, the opposite side being a mirror image of the side shown.

We claim:

The ornamental design for a light emitting gas discharge matrix display panel, as shown and described.
